TOY BOAT

Ernest L. Thornell, East Aurora, N.Y., assignor to Fisher-Price Toys, Inc., East Aurora, N.Y., a corporation of New York

Filed Mar. 6, 1967, Ser. No. 6,064

Term of patent 14 years

(Cl. D34—15)

FIG. 1

FIG. 3

FIG. 1 is a perspective view of a toy boat showing my new design;

FIG. 2 is a top plan view thereof; and
FIG. 3 is a bottom plan view thereof.

I claim:

The ornamental design for a toy boat, substantially as shown.
